US00D725160S

(12) **United States Design Patent**
Lee et al.

(10) **Patent No.:** US D725,160 S
(45) **Date of Patent:** ** Mar. 24, 2015

(54) **PANELS**

(71) Applicant: **Samsung Electronics Co., Ltd.**, Suwon-Si, Gyeonggi-Do (KR)

(72) Inventors: **Heame Lee**, Seoul (KR); **Myeonghee Bak**, Seoul (KR); **Jidam Hong**, Seoul (KR)

(73) Assignee: **Samsung Electronics Co., Ltd.**, Gyeonggi-do (KR)

(**) Term: **14 Years**

(21) Appl. No.: **29/450,776**

(22) Filed: **Mar. 22, 2013**

(30) **Foreign Application Priority Data**

Nov. 16, 2012 (KR) 30-2012-0054986

(51) **LOC (10) Cl.** **15-07**

(52) **U.S. Cl.**

USPC **D15/89**

(58) **Field of Classification Search**
